US00D914740S

(12) **United States Design Patent** (10) Patent No.: **US D914,740 S**
Clymer et al. (45) Date of Patent: **** Mar. 30, 2021**

(54) **DISPLAY SCREEN OR PORTION THEREOF WITH GRAPHICAL USER INTERFACE**(71) Applicant: **Lutron Technology Company LLC**, Coopersburg, PA (US)(72) Inventors: **Erica L. Clymer**, Northampton, PA (US); **Praneetha Jonnala**, Allentown, PA (US); **James Mathias Weber**, Allentown, PA (US); **Jennifer Wong**, Breinigsville, PA (US)(73) Assignee: **Lutron Technology Company LLC**, Coopersburg, PA (US)(**) Term: **15 Years**(21) Appl. No.: **29/732,187**(22) Filed: **Apr. 22, 2020****Related U.S. Application Data**

(63) Continuation of application No. 29/689,882, filed on May 2, 2019, now Pat. No. Des. 883,321, which is a continuation of application No. 29/621,353, filed on Oct. 6, 2017, now Pat. No. Des. 848,471, which is a continuation of application No. 29/575,797, filed on Aug. 29, 2016, now Pat. No. Des. 802,622.

Primary Examiner — Kathleen L Jones*(74) Attorney, Agent, or Firm* — Saidman DesignLaw Group, LLC(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.

1 Claim, 1 Drawing Sheet(56)
